(57) **CLAIM**

The ornamental design for a solid-state memory module, as shown and described.

DESCRIPTION

FIG. 1 is a perspective view of a solid-state memory module according to my new design;

FIG. 2 is a top view of the solid-state memory module according to my new design;

FIG. 3 is a bottom view of the solid-state memory module according to my new design;

FIG. 4 is a front view of the solid-state memory module according to my new design;

FIG. 5 is a rear view of the solid-state memory module according to my new design; and,

FIG. 6 is a left side view of the solid-state memory module according to my new design, the right side being a mirror image thereof.

The portions of the solid-state memory module shown in broken lines form no part of the claimed design.
